SIGNAL TRANSMISSION SYSTEM

Henri G. Busignies, Forest Hills, N. Y., assignor
to Federal Telephone and Radio Corporation, a
corporation of Delaware

Application October 7, 1942, Serial No. 461,143

18 Claims. (Cl. 250—20)

1

This invention relates to radio receiving systems and more particularly to time modulated impulse receivers.

For purposes of power economy and other uses, transmission of signals by time modulated impulses has been resorted to as described in U. S. patents to A. Reeves Nos. 2,266,401 and 2,256,336 and U. S. patent to E. Deloraine and A. Reeves No. 2,262,838. By the use of these pulse systems, either single pulses variable in length or pairs of pulses adjusted in time with respect to one another, it is possible to transmit and receive energy provided only that the spacing or length of the pulses is controlled in time in accordance with the modulating signal.

It has been proposed in pulse modulation systems to provide receivers in which a relatively simple tuned filter circuit is provided to convert the time modulated pulses into amplitude modulated signals so that they may be audibly reproduced. Such systems are described more fully in the application of E. Deloraine and E. Labin entitled "Pulse transmission system," Serial No. 425,108, filed December 31, 1941, and the application of E. Labin entitled "Radio receiver," Serial No. 449,595, filed July 3, 1942. This system works very satisfactorily but requires a relatively constant recurrence interval between the time modulated pulse pairs since the harmonic content of the wave and its variations must be properly controlled.

It is an object of my invention to provide a system for converting pulse modulation into amplitude modulation in accordance with the duration of a pulse formation without any interdependence upon the recurrence frequency of the pulse formations.

According to a feature of my invention, the object outlined above and others are accomplished by providing means responsive to the received pulse formations for producing wave trains of a given frequency and an amplitude dependent upon the duration of the pulse formation and further means for terminating the wave trains prior to the reception of the succeeding pulse formation.

A better understanding of my invention and the objects and features thereof may be had from the particular description thereof made with reference to the accompanying drawings, in which—

Fig. 1 is a block diagram of a receiver system embodying the features of my invention;

Fig. 2 is a set of curves used to explain the operation of the receiver in accordance with my invention;

Fig. 3 is a circuit diagram of a tuned oscillating circuit which may be part of the circuit of Fig. 1;

Fig. 4 is a modified tuned oscillating circuit

2

which may be part of the system of Fig. 1; and Fig. 5 is a set of curves used to explain further features of my invention.

In Fig. 1, a receiver element 10 is provided for receiving and amplifying pulse modulation signals in the manner of the usual R. F. and I. F. stages. These pulse modulation signals may be passed to demodulator and reshaper circuit 11 and from there passed to a tuned oscillation circuit 12 preferably a shock excited circuit which 5 is provided with means such as the inherent damping of the circuit for terminating the produced wave prior to the reception of the succeeding group of pulses. The waves produced in tuned circuit 12 are then detected in a detector 10 amplifier circuit 13 and applied to headphones 14. In the event that amplitude modulation of the pulses is present as well as time modulation thereof, an auxiliary amplitude modulation detector amplifier 15 may be provided with suitable 15 translating apparatus 16.

In accordance with my invention the wave trains produced in the tuned oscillating circuit 12 are given amplitude characteristics dependent upon the spacing of the received pulse formations but substantially independent of the recurrence frequency of these pulse formations. A better understanding of the operation of the receiver may be had from the following description made with reference to Fig. 2. In this figure, curve A represents pulse formations which 20 are produced in a known manner in the output of demodulator reshaper 11 in response to pulse signals received at 10. These pulses may be 25 substantially square wave formations as shown in curve A for the most efficient operation. It should be understood, however, that the system described is operative for other pulse formations as well. Pulses 20 and 21 form one pulse formation and pulses 22 and 23 correspond to the 30 succeeding pair of pulses of the chain of received signal pulses have been reshaped, the recurrence period R of the pulse formations may be any 35 desired amount. For example, this period R may be varied from 30 to 80 microseconds, this 40 variation, of course, being controlled at the source of the signal pulses. Pulses 20 and 21 are controlled in width at 11 and in the present instance 45 may be considered as being one half a microsecond in width. The interval between the two 50 pulses which as measured between leading edges thereof is indicated as P varies according to the intelligence with which the received signal pulses 55 are modulated. When pulse 20 is applied to the shock excited tuned circuit, it immediately produces therein a wave formation shown at 30, curve B. The circuit is tuned to one megacycle 60 frequency so that one alternate or half a wavelength of the wave produced in the circuit will occur during the pulse width period D. By

choosing this particular frequency, the leading edge and trailing edge of the pulse both act in phase on the generating wave and thus produce a stronger oscillation. In one extreme position of modulation as illustrated in the solid line pulse 21, this pulse when applied to the same shock excited circuit tends to produce an oscillation 180° out of phase with the oscillation produced by pulse 20 as shown by the light line curve 31. This pulse accordingly serves to modify wave 30 and substantially kills the oscillation producing the resultant wave shown in the heavy line curve 32.

Upon modulation of the pulses in time, pulses 20 and 21 move toward one another as shown by the dotted lines 44 and 45 of curve A. Accordingly, the successive effects of pulses 20 and 21 on tuned circuit 12 is no longer such as to completely damp out the wave but tends to produce two wave formations 40 and 41 as shown in curve C which together produce the resultant curve 42 shown in heavy lines in curve C.

Curves B and C may be considered as representing the extreme modulation positions of pulses 20 and 21. For intermediate modulation positions of pulses 20 and 21 there will be produced wave trains of varying amplitude in accordance with the variation in spacing of the modulated pulses. Accordingly, when these successively produced wave trains are detected at 13, the modulation envelope of the time modulated pulses will be reproduced. This envelope may be further amplified, if necessary, and applied directly to headphones or a loudspeaker or any other desired translating device.

It can thus be seen that the successively received pulse formations serve to produce wave trains varying in amplitude in accordance with the duration of the pulse formation interval independently of the recurrence frequency R between the pulses. However, in order to assure that there is no interaction between successively received pulse formations, it is desirable that the tuned oscillating circuit be controlled so that the wave formations produced therein do not endure for a period greater than the time spacing of these pulse formations. This may simply be accomplished by having tuned circuit 12 of such damping characteristics as to reduce the waves substantially to zero prior to the initiation of new oscillations by the succeeding received pulse formation. This action is indicated by the dotted triangles 33, 43 shown in curves B and C respectively.

When square waves such as 20 and 21 are produced in the demodulator and reshaping circuit, it is clear that only the odd harmonics will be present in the system. Thus for this type of waves the tuned circuit must be properly related to one of these harmonic frequencies. Thus the frequency must be chosen so that

$$F = (2n-1) \frac{1}{2D}$$

where F is the frequency and n is any integer and D is the pulse width. With the value of n in the above equation chosen as 2, the wave formations produced by pulses 20 and 21 in their successive positions may be in the form shown in curves D and E respectively of Fig. 2.

A suitable form of tuned oscillating circuit for operating to produce the wave formations shown in Fig. 2 is illustrated in more detail in Fig. 3. In this figure, the tuned oscillating circuit 12 is shown generally in broken lines. The output

from demodulator 11 is applied to the input grid 63 of vacuum tube 60 across the anode 64 and cathode 65 of which is connected a tuned circuit comprising an inductance 61 and condenser 62. This tuned circuit is adjusted to have the proper frequency and to have sufficient damping to reduce the waves generated substantially to zero before a second pulse formation is applied thereto. The output circuit connected across the tuned circuit may then be applied directly to the detector arrangement 13 as shown in Fig. 1.

The curves shown in Fig. 2 are all shown as being highly damped to assure termination of the wave trains at a desired interval. In some cases, however, it may be preferable to use a tuned circuit which is not highly damped and to provide means for terminating oscillation of this circuit at a desired period after the reception of pulses. By using the higher "Q" tuned circuit, greater amplitude of the received signals will be assured and the system therefore will be more sensitive to the reception of signals.

A suitable arrangement for accomplishing this result is illustrated in Fig. 4 which shows a particular circuit arrangement for tuned oscillating circuit 12. In this case, pulses 20 and 21 are applied over a delay line 70 to a vacuum tube 60. In the output of vacuum tube 60 is provided tuned circuit 61, 62 corresponding to the similar tube and circuit arrangement of Fig. 3. However, the tuned circuit is here adjusted to have very low losses so that the oscillations will tend to persist for a long period of time. Across tuned circuit 61, 62 is connected the anode 73 and cathode 74 of a variable impedance tube 71. When no energy is applied to the grid 75 of this tube, the impedance is substantially that of an open circuit so that no substantial damping of the tuned circuit will occur. I provide further a connection 76 from the input of circuit 12 to the grid 75 of tube 71 so that the received pulses will be applied to this tube causing it to be conductive and thoroughly damping any oscillations in tuned circuit 61, 62. The delay line 70 is made of sufficient length to permit passage of these pulses from the grid of tube 71 prior to the application of the pulses to the tuned circuit over tube 60.

Thus the pulses first are applied to the grid of tube 71 over time constant circuit 72, which includes condenser 77 and resistor 78, causing a damping of any oscillations in the circuit. Then these pulses are successively applied to the tuned circuit to produce the desired wave train. This wave train then persists for a period of time until the succeeding pulse formation reaches the receiver. These succeeding pulses are immediately applied to tube 71 damping out all signs of oscillation from circuit 61, 62 after which this pulse formation is applied to the tuned circuit to excite a new train of waves.

The delay line 70 may be of any desired type, for example, a resistance-condenser combination and it may comprise a variable condenser so that the length of the delay period may be controlled at will. It should be also clear that instead of putting the delay line in the input circuit of the tuned circuit, the delay line could be placed in the circuit supplying the pulses to tube 71. In this case, the period would be such as to terminate produced oscillations at a fixed time after arrival of the pulses instead of a fixed time prior to application of the succeeding pulses. This latter system, however, is generally less desirable since it requires a much longer delay period for the pulse.

In general, the system as described above wherein the pulses are varied in spacing with respect to one another is preferred, but the principles of my invention apply also to other types of pulse modulation systems. For example, the type of pulse modulation system wherein one of the pulses is fixed in time and the other one is varied in accordance with the modulation, is illustrated in curves J and K of Fig. 5. Curve J illustrates the fixed pulse 80 and variable pulse 81 shown in solid and dotted lines respectively to indicate two modulation positions. Pulse 81 in its solid line position in cooperation with pulse 80 will produce the solid line curve 82 of curve K while in the dotted line position it will produce a wave corresponding to the dotted line 83 of curve K. When this type of modulation is used, it is necessary only to transmit the variable pulse since the fixed pulse may then be locally reproduced at the receiver. However, in accordance with my system, it is generally preferable to transmit both pulses since otherwise the recurrence frequency would have to be maintained relatively stable in order that the locally produced pulse could be properly timed.

Another form of pulse modulation comprises the production of long pulses, the variation in length of which serves to indicate the time modulation. Such type of waves may also be used with a receiver embodying the principles of my invention. Curves illustrating the operation of such pulses are shown at L and M of Fig. 5. In curve L is shown a pulse 90 which may extend to the full line position as shown in solid lines or may terminate at other variable positions as shown at 91. In the full line position, the leading edge of pulse 90 tends to produce an oscillation in the shock excited circuit while the trailing edge of the pulse serves to modify the amplitude of this wave. Thus in the solid line position, the pulse will produce a solid line curve 92 shown in curve M while in the dotted line position, the dotted curve 93 will be produced.

In all of the above described systems, the operation has been illustrated in connection with pulses which have relatively straight leading and trailing edges. The principles of my invention, however, may be readily applied to any form of pulse system regardless of the particular shape thereof. Accordingly, it is not necessary to reshape the received pulses but it is entirely possible to merely demodulate them before applying them to the tuned circuit. Curves N and O of Fig. 5 serve to illustrate pulses of this general nature. In curve N there are shown two pulses 25 and 26 roughly corresponding in spacing to pairs of pulses such as shown at 20 and 21. Each of these pulses, however, has a very sharp leading edge and a relatively sloping trailing edge. When pulse 25 is applied to the tuned oscillating circuit, the leading edge will tend to produce oscillations therein. The trailing edge will tend to produce oscillations in the opposite direction but since the trailing edge is much less steep than is the leading edge, the harmonic content thereof is much less so that this edge will serve only to reduce the amplitude of the produced oscillations but will not cause extinction thereof. Similarly, the leading edge of pulses 26 will also serve to produce oscillations serving to modify those produced by the leading edge of pulse 25. When this type of pulse is used, then the harmonic frequency need not be limited to the odd harmonics as in the case of the square wave pulses. Accordingly, the two pulses 25 and 26 may serve to produce an

even harmonic wave of the type illustrated at 27, curve O of Fig. 5.

While in general it is preferable to utilize the pulse modulation in the manner described above so that one extremity of the pulse positions represents an extremity of modulation, it is possible to utilize pulses transmitted so that this is not the case. If the repetition period R is so adjusted so as to produce no resulting oscillation in the receiver in the absence of modulation, the oscillations produced in the tuned circuit will be such that the output signal will be similar to the side bands without any carrier, as in ordinary suppressed carrier audio-modulation signalling. In such case, it is necessary to supply locally the carrier oscillations prior to detection in order that the envelope may be properly reproduced.

It will also be understood that while it is preferable to have one extreme of modulation produce substantially no output energy, the system will be readily operable if this extreme of modulation is chosen to produce a maximum of energization of the oscillating circuit. In this latter case, variation of the pulse spacing will reduce the amplitude in accordance with the modulations instead of increasing it as in the given example. In general, this system, however, is not preferred since it is not as efficient as the system outlined in the specific examples.

The receiving system in accordance with my invention is readily operable for reception of pulses regardless of the recurrence period as stated above. Accordingly, means may be provided at the transmitter for continuously varying this recurrence period. With such variation of recurrence, it is much more difficult for an unauthorized person to intercept and translate the message or to produce jamming pulses to obliterate the indication.

While I have described above the principles of my invention in connection with specific apparatus and particular modifications thereof, it is to be clearly understood that this description is made only by way of example and not as a limitation on the scope of my invention as set forth in the objects of my invention and the accompanying claims.

What is claimed is:

1. In a receiving system for receiving trains of pulse formations representing variable periods of time in accordance with a modulating envelope, means for producing wave trains representing the initiation of said periods, means for modifying the amplitude of said produced wave trains in accordance with the termination of said periods, means for substantially terminating each produced wave train prior to initiation of the succeeding wave train, and means for detecting said produced wave trains to obtain said modulating envelope.

2. A receiving system according to claim 1 wherein said pulse formations representing periods of time comprise pairs of pulses variably displaced with respect to one another, and said first named means comprises a shock excited tuned circuit, and means for applying said pulses thereto.

3. A receiving system according to claim 1, wherein said first named means comprises a shock excited tuned circuit, and said second named means comprises the inherent damping characteristics of said tuned circuit.

4. A receiving system for receiving time modulated pulse energy in which the signal amplitudes are represented by the relative time dis-

placement of pairs of pulses with respect to one another comprising means for receiving said pulses, means responsive to said received pulses for producing wave trains the amplitudes of which are dependent upon said relative spacing of said pairs of pulses means for substantially terminating each of said wave trains prior to the production of the succeeding wave train, and means for detecting said wave trains to produce the modulation envelope of said received energy.

5. A receiver for producing the modulation envelope of a received wave, said wave comprising a series of pairs of pulses of radio frequency controlled in time position in accordance with a modulating wave, comprising means for receiving and reshaping said pulses, a shock excitation oscillatory circuit, means for causing excitation of said circuit to produce a wave train of a given frequency in response to reception of the first pulse of said pair, means responsive to the second pulse of said pair for modifying the amplitude of said wave train in accordance with the time position of said second pulse, means for substantially terminating said wave train prior to reception of the succeeding pulse pair, and means for detecting said modified wave trains to reproduce said modulation envelope.

6. A receiver according to claim 5 wherein said means for terminating said modified wave trains comprises the inherent damping characteristics of said circuit.

7. A receiver according to claim 5 wherein said means for terminating said modified wave trains comprises, normally high impedance means connected across said circuit, and means responsive to received signals for effectively lowering the impedance of said normally high impedance means to damp the oscillation of said circuit.

8. In a receiver for successive pulses of energy, means responsive to a received pulse for producing a predetermined wave train, and means responsive to the following received pulse for terminating said wave train.

9. In a receiver for a series of pulse formations, circuit means for generating wave trains, circuit means for terminating the generation of said wave trains, means for applying said pulse formations to said circuit means for generating wave trains and said circuit means for terminating said wave trains, and delay means for producing a relative time delay between application of said pulse formations to said respective circuit means.

10. A receiver according to claim 9 wherein said pulse formations each comprise a pair of pulses, said first named circuit means comprising a tuned circuit shock excited into oscillation by the first pulse of said pairs to produce wave trains and excited by the second pulse of said pair to modify the produced wave trains in accordance with the spacing of said pulses.

11. A receiver according to claim 9 wherein said pulse formations each comprise a pair of pulses, said first named circuit means comprising a tuned circuit shock excited into oscillation by the first pulse of said pairs to produce waves forming said trains and excited by the second pulse of said pair to modify the produced waves in accordance with the spacing of said pulses, and said second named circuit means comprise a variable impedance shunt connected across said tuned circuit, and means in said shunt connection for reducing said impedance in response to said applied pulse formations.

12. A receiver according to claim 9, further

comprising detector means for detecting said generated terminated wave trains to produce the envelope frequencies of said series of pulse formations.

13. A receiver according to claim 9 wherein said pulse formations each comprise a pair of pulses, said first named circuit means comprising a tuned circuit shock excited into oscillation by the first pulse of said pairs to produce a wave train and excited by the second pulse of said pair to modify the produced wave trains in accordance with the spacing of said pulses, further comprising detector means for detecting said generated terminated wave trains to produce the envelope frequencies of said series of pulse formations.

14. A receiver according to claim 9 wherein said pulse formations each comprise a pair of pulses, said first named circuit means comprising a tuned circuit shock excited into oscillation by the first pulse of said pairs to produce wave trains and excited by the second pulse of said pair to modify the produced wave trains in accordance with the spacing of said pulses, and said second named circuit means comprise a variable impedance shunt connected across said tuned circuit, and means in said shunt connection for reducing said impedance in response to said applied pulse formations, further comprising detector means for detecting said generated terminated wave trains to produce the envelope frequencies of said series of pulse formations.

15. In a receiving system for receiving trains of pulse formations representing variable periods of time in accordance with a modulating envelope, means for producing wave trains representing the initiation of said periods, and means for modifying the amplitude of the produced wave trains in accordance with the termination of said periods.

16. In a receiving system for receiving trains of pulse formations representing variable periods of time in accordance with a modulating envelope, means for producing wave trains representing the initiation of said periods, means for modifying the amplitude of the produced wave trains in accordance with the termination of said periods, and means for detecting the produced wave trains to obtain said modulating envelope.

17. In a receiving system for receiving trains of pulse formations representing variable periods of time in accordance with a modulating envelope, the method of demodulating the time modulation of said pulses comprising producing wave trains each representing the initiation of one of said periods, and modifying the amplitude of each wave train by the termination of the corresponding period.

18. A method according to claim 17 further including the step of substantially terminating each of said wave trains prior to initiation of the succeeding wave train.
